UNITED STATES PATENT OFFICE

ARCADY N. SHOLKING, OF MANILA, PHILIPPINE ISLANDS

ENGINE

Application filed November 7, 1930. Serial No. 494,119.

This invention relates to an internal combustion engine and more particularly to new and useful improvements in devices of this character of the two cycle type and has for 5 one of its important objects to provide, in a manner as hereinafter set forth, an engine embodying a reciprocating inner cylinder in which is mounted for reciprocation a piston which cooperates with the reciprocating cylinder to compress the fuel charge to a degree which will cause the ignition thereof, thus dispensing with the use of a means such as spark plugs for igniting the charge.

Another important object of the invention 15 is to provide an engine of the character described which includes means for compressing the fuel charge before charge enters the combustion chamber of the engine.

Other objects of the invention are to provide an internal combustion engine which will be simple in construction, strong, durable, efficient in operation and which may be manufactured at low cost.

All of the foregoing and still further objects and advantages of the invention may 25 become apparent from a study of the following specification, taken in connection with the accompanying drawings, wherein like characters of reference designate corresponding parts throughout the several views, and wherein;

Figure 1 is a view in vertical section showing the arrangement of the cylinders and the pistons which form an essential portion of 35 the invention.

Figure 2 is a view in vertical section showing the means for operatively connecting the reciprocating cylinder and the piston with the driven shaft.

Figure 3 is a detailed view in cross section 40 through the driven shaft and showing, in side elevation, one of the disks having cam grooves therein for the reception of the connecting rods of the reciprocating cylinder and the piston.

Figure 4 is a horizontal cross sectional view 45 taken substantially on the line 4—4 of Figure 1.

Figure 5 is a detail view in section showing 50 the means for operatively engaging the con-

nnecting rods with the disks which are fixed on the driven shaft.

Figure 6 is a vertical sectional view taken substantially on the line 6—6 of Figure 1 looking in the direction indicated by the arrows.

Referring the drawings in detail, it will be seen that the reference numeral 1 designates a portion of a casing in which is journaled the driven shaft 2 which is of hollow construction and has formed integrally thereon the flange 3. An outer stationary cylinder 4 is rigidly mounted on the casing 1 by suitable bolts 5 and the stationary cylinder 4 is provided with an enlarged lower end portion 6. The stationary cylinder 4 is further provided, in an intermediate portion, with an exhaust port 7 and adjacent its upper end the stationary cylinder 4 is further provided with an intake port 8. An integral flange 9 is formed on the outer periphery of the stationary cylinder 4 adjacent the intake port 8 and below said intake port.

A head designated generally by the reference numeral 10 is detachably mounted over the upper end portion of the stationary cylinder 4 and comprises the depending skirt portion 11 which is disposed in spaced, concentric relation to the upper end portion of the stationary cylinder 4. The skirt 11 has formed integrally on its lower end an in-turned flange 12 for rest on the flange 9 and bolts 13 pass through the flanges 9 and 12 for securing the head 10 on the stationary cylinder 4. The upper wall 14 of the head 10 is spaced above the open upper end of the stationary cylinder 4 as clearly seen in the drawings.

The stationary cylinder 4 is provided, on the side thereof opposite to the side in which the exhaust port 7 is located, with an intake port 15 which periodically communicates with the chamber 16 in the lower portion of the stationary cylinder 4. The chamber 16 constitutes a compression chamber to be more fully hereinafter described relative to its function and a by-pass 17 (these Figures 4 and 1) communicate at its lower end, with the chamber 16 and at its upper end with the compression chamber 18 provided by the up-

per end portion of the stationary cylinder 4 and the head 10.

An inner cylinder 19 is mounted for reciprocation in the stationary cylinder 4 and is provided, adjacent its upper end, with an intake port 20 for registry with the port 8. The reciprocating cylinder 19 is further provided at a point in spaced relation below the port 20, with an exhaust port 21 for registry with the exhaust port 7. On its other side the reciprocating cylinder 19 is provided with a port 22 for registry with the port 15 for periodically admitting the fuel charge to the chamber 16 through the port 15.

15 A piston 23 is mounted for reciprocation in the reciprocating cylinder 19 and is provided with a concave upper end 24 which provides a compression chamber 26 between the upper ends of the piston 23 and the upper 20 end of the reciprocating cylinder 19.

A pair of spaced, opposed disks 27 are fixed on the driven shaft 2 in abutting engagement with opposite sides of the flange 3 and the disks are retained in position by 25 suitable collars 28. On the outer sides each of the disks 27 is provided with a cam groove 29 and on their inner or opposed sides the disks 27 are provided with the complementary cam grooves 30. The cam grooves 29 and 30 are of the configuration illustrated to advantage in Figure 3 of the drawings and the grooves 30 are disposed at right angles to the grooves 29. A connecting rod 31 extends slidably through the outer wall 32 of the casing 1 and has one end threadedly connected to the piston 23, as at 33. The other end portion of the piston rods 31 has mounted transversely therein and projecting from the opposite sides thereof a pintle 34 the end 35 portion of which are disposed in the cam grooves 30 and has mounted thereon suitable anti-friction bearings 35 for travelling in the grooves 30.

40 Sleeve bearings 36 extend through the outer wall 32 of the casing 1 on opposite sides of the piston rod 31 and slidably receive the connecting rod 37 having one end threadedly connected to the lower end portion of the reciprocating cylinder 19, as at 38. A pintle 39 extends laterally from the other end portion of each of the connecting rods 37 into the adjacent end groove 29 and anti-friction bearings 40 are provided on the pintle 39 for travel in the cam grooves 29.

45 In operation, the arrangement of the cam grooves 29 and 30 will cause the piston 23 and the reciprocating cylinder 19 to move in opposite directions simultaneously relative to each other. Thus, when the piston 23 moves 50 upwardly and the reciprocating cylinder 19 moves downwardly to the position illustrated in Figure 2 of the drawings, a partial vacuum will be formed in the chambers 16 and 18 and when the port 22 registers with the port 55 15 the fuel charge from a suitable manifold

(not shown) will rush into the chamber 16 beneath the piston 23. A portion of this fuel charge passes through the by-pass 17 into the compression chamber 18. It will be seen that in this position the piston 23 is disposed above the port 22 in the reciprocating cylinder 19 to permit the passage of the fuel into the chamber 16. On the down stroke of the piston 23 and on the upstroke of the reciprocating cylinder 19 the port 15 is closed and the fuel 75 will be compressed in the chambers 16 and 18. When the reciprocating cylinder 19 reaches the limit of its upward movement the port 20 is brought into registry with the port 8 and the compressed fuel from the chambers 16 80 and 18 rushes into the reciprocating cylinder 19 above the piston 23, the fuel from chamber 16 passing through the by-pass 17. The piston 23 and the reciprocating cylinder 19 then move toward each other and compress 85 the charge which has entered the reciprocating cylinder 19 to such a degree that same will be caused to ignite, it being understood, of course, that when the reciprocating cylinder 19 moves downwardly on this compression stroke that communication between the port 8 and 20 is broken. As will be apparent, when the fuel charge in the reciprocating cylinder 19 ignites, the piston 23 is again 90 driven downwardly and the reciprocating cylinder 19 is driven upwardly and the exhaust port 21 therein is brought into registry with the exhaust port 7 in the stationary cylinder 4. This occurs slightly in advance of 95 the registering of the ports 20 and 8 on the upstroke of the reciprocating cylinder 19. The new charge entering the upper portion of the reciprocating cylinder 19 blows the exhaust gases out through the exhaust ports 21 and 7. At this point in the operation of 100 the engine the piston 23 is disposed below the exhaust port 21 in the reciprocating cylinder 19, as clearly seen in Figure 1 of the drawings. As will be apparent, reciprocation of 105 the piston 23 and the cylinder 19 will impart rotary movement to the shaft 2.

The arrangement herein illustrated and described is particularly intended for use in the construction of engines of the radial type and any number of the cylinders may be provided but the invention may be incorporated in other types of internal combustion engines if it is so desired.

110 It is believed that the many advantages of an internal combustion engine constructed in accordance with this invention will be readily understood, and although the preferred embodiment of the invention is as illustrated and described, it is to be understood that changes in the details of construction may be had which will fall within the scope of the invention as claimed.

115 What is claimed is:

120 1. An engine of the character described comprising a casing, a shaft journaled in the 125

casing, a stationary cylinder mounted on the casing having a compression chamber in each end portion, and further having a by-pass communicating with the compression chambers, the stationary chamber being still further provided with a port communicating with one of the compression chambers, a cylinder mounted for reciprocation in the stationary cylinder, the reciprocating cylinder being provided with a port adapted for registry with the first named port and being further provided with an intake port for communication periodically with the other of the compression chambers, the stationary and reciprocating cylinders being so further provided with exhaust ports, adapted to be periodically brought into registration with each other, a piston mounted for reciprocation in the reciprocating cylinder, and means operatively connecting the reciprocating cylinder and the piston to the shaft in a manner to actuate said shaft, said means comprising a pair of faces, opposed disks fixed on the shaft and having complementary cam grooves on their opposed sides and further having cam grooves on their outer sides disposed at right angles to the complementary cam grooves, a rod rigidly connected to the piston and extending slidably into the casing, a cross pin on the rod having its end portions disposed for travel in the complementary end grooves for operatively connecting the rod to the disks, rods rigidly connected to the reciprocating cylinder at diametrically opposite sides thereof and extending slidably into the casing adjacent the outer sides of the disks, and pintles extending laterally from the last named rods and extending into the adjacent cam grooves in a manner to operatively connect the last named rods to the disks.

2. An engine of the character described comprising a casing, a shaft journaled in the casing, a stationary cylinder mounted on the casing having a compression chamber in each end portion and further having a fuel intake port communicating with one of the compression chambers, the stationary cylinder being further provided with a by-pass extending from said one compression chamber to the other compression chamber and being so further provided with an exhaust port intermediate the compression chambers, a cylinder mounted for reciprocation in the stationary cylinder and having an intake port therein adapted to be periodically brought into communication with said other compression chamber for the passage of fuel into the reciprocating cylinder, said reciprocating cylinder being so provided with a port for periodical registration with the fuel intake port in the outer cylinder for the passage of the fuel charge into the one compression chamber, the reciprocating cylinder being so further provided with an exhaust port for periodical registration with the exhaust port in the stationary cylinder, a piston mounted for reciprocation in the reciprocating cylinder and having a concavity in one end, a piston rod rigidly connected to the other end of the piston and extending slidably into the casing, a pair of faces, opposed disks fixed on the shaft and extending on opposite sides of the piston rods, complementary cam grooves in the opposed sides of the disks, a cross pin fixed transversely in the piston rods and extending into the complementary grooves, bearings mounted on the end portions of the cross pins for travel in the complementary grooves, rods rigidly connected to diametrically opposite sides of the reciprocating cylinder and extending slidably into the casing, pintles extending laterally from the last named rods, the outer sides of the disks being further provided with cam grooves disposed substantially at right angles to the first named cam grooves, the pintles extending into the last named cam grooves in a manner to operatively connect the last named rods to the disks, and anti-friction bearings mounted on the pintles for travel in the last named cam grooves.

3. An engine of the character described comprising a casing, a shaft journaled in the casing, a stationary cylinder mounted on the casing and projecting therefrom and having a compression chamber in its inner and outer end portions, the stationary cylinder being further provided with an intake port for the passage of fuel into the inner compression chamber and being further provided with a by-pass communicating with the inner and outer compression chambers, the stationary cylinder being further provided with an exhaust port intermediate the compression chambers and with a port adjacent its outer end, an integral circumferentially extending flange on the stationary cylinder intermediate the exhaust port and the last named port, a head disposed over the outer end portion of the stationary cylinder and including a skirt portion disposed in spaced concentric relation to the outer end portion of the stationary cylinder and further including an end wall disposed in spaced relation to the outer end of the stationary cylinder, an integral inturned flange on the skirt for abutting engagement on the flange of the stationary cylinder, securing elements clamping the flanges together, a cylinder mounted for reciprocation in the stationary cylinder and having an intake port in one end portion thereof for periodical registration with the last named port in the stationary cylinder for the passage of fuel from the outer compression chamber into the reciprocating cylinder, said reciprocating cylinder being further provided with a port for periodical registration with the first named port in the stationary cylinder for the passage of fuel

into the inner compression chamber and being so further provided with an exhaust port for periodical registration with the exhaust port in the stationary cylinder for the passage of gases outwardly from the reciprocating cylinder, a piston mounted for reciprocation in the reciprocating cylinder, and means operatively connecting the piston and the reciprocating cylinder to the shaft for actuating said shaft and for causing movement simultaneously in opposite directions of the piston and the reciprocating cylinder relative to the other, said means comprising a pair of faces, opposed disks fixed on the shafts and having complementary cam grooves in their opposed sides and further having cam grooves in their outer sides disposed at right angles to the first named cam grooves, a piston rod rigidly connected to the pistons and extending slidably into the casing and between the disks, a cross pin mounted on the piston rods and extending into the first named cam grooves for operatively connecting the piston rods to the disks, bearings on the portions of the cross pins, rods rigidly connected to diametrical sides of the reciprocating cylinder and extending slidably into the casing adjacent the outer sides of the disks, pintles extending laterally from the last named rods into the last named cam grooves, for operatively connecting the last named rods to the disks and bearings mounted on the pintles for travel in the last named cam grooves.

35 In testimony whereof I affix my signature.
